LAMP HOLDER

Frank C. De Reamer, Bridgeport, Conn., assignor
to General Electric Company, a corporation of
New York

Application November 6, 1936, Serial No. 109,472

13 Claims. (Cl. 173—328)

The present invention relates to lamp holders and particularly to lamp holders for holding lamps of the type wherein the lamp base is provided with prongs which fit into sockets in the holder. The invention is especially adapted for use with lamps of relatively high wattage, such as are used in motion picture projectors, air port lighting and the like, although it is not limited thereto necessarily but may be used wherever found applicable.

The primary object of my invention is to provide an improved construction of lamp holder into which the lamp prongs are easily inserted and fixed in place, which holds the lamp firmly and with good electric contact, and wherein the lamp is accurately positioned relatively to the support so that its filament may be accurately located.

A further object of my invention is to provide a lamp holder which is relatively simple and rugged in structure, easy to install and use, and capable of being manufactured at low cost.

For a consideration of what I believe to be novel and my invention, attention is directed to the following specification and the claims appended thereto.

In the drawing, Fig. 1 is a side view of a lamp holder embodying my invention, a lamp of the prong contact type being shown in the holder; Fig. 2 is a side view partly in section of the holder, one prong of a lamp being shown in its socket but not clamped therein; Fig. 3 is a top plan view of the holder looking in the direction indicated by line 3—3 of Fig. 2; Fig. 4 is a transverse sectional view taken on the line 4—4 of Fig. 2, and Fig. 5 is a sectional view of a modification.

Referring to the drawing, 1 indicates a base of insulating material divided centrally at one side by an upstanding partition wall 2 in line with which are countersunk openings 3 to receive screws or other fastening means for attaching the flat bottom 4 of the base against a support. Mounted on the base on opposite sides of the partition wall 2 are relatively heavy rectangular bars 5 which form combined terminal and socket members. The members 5 are suitably mounted on posts 6 which are fixed in openings in base 1 and project vertically above the base on opposite sides of partition wall 2. The combined terminal and socket members 5 are provided with tubular rivets 7 which provide openings which fit posts 6, the rivets being suitably fixed in place by having their outer ends upset. The posts 6 are shown in the present instance as being held in the openings

in base 1 by the lower upset ends of the rivets and by a bottom washer 7a fastened to the lower ends of the posts 6. It will be understood however that any suitable arrangement may be used.

As shown particularly in Figs. 3 and 4, the bars 5 are spaced slightly from the side surfaces of upstanding wall 2 as is indicated at 8 and the arrangement is such that either one or both of the bars 5 is sufficiently loose on its post 6 that it may pivot slightly thereon. At one end each of the bars 5 is provided with a binding post 9 with which the electric circuit for the lamp may be connected and at the other end each is provided with an upstanding wall 10 in the face of which is a V-shaped notch 11 which forms one side wall of a lamp prong socket. The other side wall of each lamp prong socket is formed by means of a spring arm 12 which at its lower end extends under bar 5 and is fixed thereto by means of the flange at the lower end of rivet 7, 20 rivet 7 thus moving to fasten the spring arm to the bar and electrically connect it thereto. The arm 12 is of spring material and forms a movable socket wall adapted to be moved toward a lamp prong to clamp it in the socket. The upstanding 25 wall 2 is located between the two bars 5 so as to form an insulating wall or barrier between them.

The spring arms 12 are adapted to be moved inwardly toward the surfaces of the V-shaped notches 11 by means of cams 13 of insulating 30 material fixed in spaced relation to each other on a shaft 14. The active parts of cams 13 are surfaced with metal strips 13a which engage the spring arms 12 to prevent wearing of the insulating material from which the cams are constructed. The cams are fixed to turn with shaft 14 preferably by employing a rectangular shaft as shown particularly in Fig. 4, which fits into rectangular openings through the cams, the cams being spaced relatively to each other by means 40 of a tubular sleeve 15 surrounding the shaft between the cams. Shaft 14 is provided at its ends with grooves 16 (Fig. 4) which form circular bearing sections for the shaft and these bearing sections fit into inwardly facing U-shaped slots 45 17 in arms 18, the arms in turn being supported by resilient brackets 19 the ends of which are riveted against the underside of the base 1 as is indicated at 20. The resilient brackets 19 are preferably made from flat spring material and 50 adapted to yield outwardly when the cams are turned to move arms 12 toward the surfaces of the V-shaped notches 11 so as to be placed under tension. On one end of shaft 14 is fixed an operating handle 21, the same being held in position 55

by a set screw 22 as shown in Fig. 3. When the handle 21 is in down position as shown in Fig. 2, the active parts of cams 13 are moved from engagement with spring arms 12 permitting the 5 spring arms to move outwardly. When the handle 21 is moved upward to the position shown in Fig. 1, the active portions of the cams are brought into engagement with spring arms 12 forcing them inwardly as is shown in Fig. 1. The 10 cams have flat faces which engage the spring arms when in the position shown in Fig. 1 which serves to give a broad engagement between the cams and the spring arms and also to form a definite stop position in which the cams are held 15 when the handle is in its upward clamping position.

In the drawing, 25 indicates a lamp having prong contacts 26.

Instead of locating the handle 21 at one end 20 of the holder as shown in Figs. 1 to 4, it may be located at the middle of the holder as is shown in Fig. 5. In Fig. 5 21^a indicates a handle mounted on the central portion of shaft 14^a, it being held in spaced relation to the cams 13^a on shaft 25 14^a by means of two sleeves 15^a. Otherwise, the construction shown in Fig. 5 may be the same as that illustrated in Figs. 1 to 4.

The top surfaces 27 of walls 10 are located a 30 definite and accurate distance above the bottom face 4 of the base and serve as a stop with which the shoulders 28 on the lamp prongs engage thus accurately positioning the lamp in the socket. With this arrangement, the lamp occupies always the same position relatively to the 35 holder so that, for example, in the case of a motion picture projector, with the holder correctly mounted in the projector the lamp may be located always so that its filament is correctly positioned.

40 To mount a lamp in the holder, the handle 21 is moved to the down position shown in Fig. 2, so as to move the active parts of the cam 13 away from spring arms 12 permitting the arms to move outwardly away from walls 10. The 45 lamp is then positioned with its prongs 26 in the sockets and with the shoulders 28 against the top surfaces 27 of the walls 10. The handle 21 is then moved upwardly bringing the active portions of the cams into contact with the spring 50 arms 12 thus forcing the arms firmly against the prongs 26 so as to hold the prongs firmly in position and provide good electric contact, the flat surfaces of the cams then resting against the arms 12 as shown in Fig. 1 and being retained 55 in such position by the spring action of arms 12. As the cams are moved the spring arms 12 are first brought into engagement with prongs 26 after which further movement of the cams causes outward movement of brackets 19. 60 Brackets 19 are thus placed under tension and serve to force arms 12 into firm engagement with the prongs 26. The lamp is thus firmly connected to the socket both electrically and mechanically. To remove the lamp it is merely necessary to move handle 21 back to the Fig. 2 65 position. The lamp prongs are then released so that the lamp is easily lifted from the socket. This is of particular advantage when removing a lamp which is hot.

70 By having one or both of the bars 5 mounted so that it can pivot slightly, the V-shaped notches can adjust themselves so as to make firm, accurate engagement with the lamp prongs over a large surface. This is important for lamps of 75 this type may operate with current values of as

much as 100 amperes. By my invention, I provide a lamp holder which is simple in structure and readily capable of being built for large amperage lamps.

What I claim as new and desire to secure by 5 Letters Patent of the United States, is:

1. In a lamp holder, a base, spaced prong sockets on the base, each having a movable wall, a shaft, cam means mounted on the shaft for moving said walls to clamp lamp prongs in the 10 socket, yielding means supporting said shaft, and means for turning said shaft to move said cam means into engagement with said movable wall, the engagement of said cam means with said movable wall biasing said yielding means where- 15 by said movable wall is held in yielding engagement with the lamp prongs.

2. In a lamp holder, a base, spaced members pivotedly mounted on the base and provided with end surfaces, spring arms, the arms at one end 20 being connected to their respective members and at the other end extending in front of said end surfaces and forming therewith sockets to receive the contact prongs of a lamp, and means engaging the arms to flex them toward said end 25 surfaces to clamp the contact prongs of a lamp in the sockets.

3. In a lamp holder, a base, spaced members mounted on the base having notched portions providing end surfaces extending transversely of 30 said members, flexible spring arms having their ends in front of said end surfaces and forming therewith sockets to receive the contact prongs of a lamp, and means for flexing said arms relative to said notched portions to clamp the contact prongs of a lamp in the sockets.

4. In a lamp holder, a base, spaced bars mounted on the base having binding terminals at one end and lamp-prong engaging surfaces at the other end extending transversely of said bars, 40 flexible spring arms secured to the longitudinal portions of said bars and having portions extending parallel to said transverse end surfaces and forming therewith lamp-prong receiving sockets, and means for flexing said spring arms 45 in a direction axially of said bars toward said surfaces for clamping lamp prongs in the sockets.

5. In a lamp holder, a base, spaced prong sockets on the base, each having a movable wall, a shaft, yieldable spring means on which said 50 shaft is pivoted, and cam means mounted on the shaft for engaging and moving said walls to clamp lamp prongs in the sockets, the engagement of said cam means and movable wall biasing said yielding spring means whereby said movable wall is yieldingly held in engagement with the lamp prongs.

6. A lamp holder comprising a base, spaced prong sockets pivotally mounted on said base and adapted to receive the prongs of a lamp, 60 each of said sockets having a movable wall, means operating said movable wall into engagement with said prongs to hold the prongs in said sockets, and yielding means supporting said operating means upon said base.

7. In combination, a base having a partition, spaced bars pivotally mounted on said base on opposite sides of said partition, sockets formed on said bars including yielding strip members fixed to a portion of said bars and cooperating with the ends of said bars to receive the prongs of a lamp, spaced cam members cooperating with said yieldable members, a shaft supporting said cam members, yielding means supporting said 70 cam members, yielding means supporting said 75

- shaft and cam-operating means fastened to said shaft.
8. In a lamp holder, a base, spaced bars mounted on said base, one end of each of said bars being notched, yieldable members cooperating with said notches to form sockets to receive the prongs of a lamp, a shaft, spaced cam means mounted on said shaft and adapted to move said members, and yielding means supporting said shaft upon said base.
9. In a lamp holder, a base, spaced bars pivotally mounted on said base, said bars having prong receiving sockets at one end and binding terminals at the other end, each of said sockets comprising a fixed wall integral with a bar and a movable wall spaced from and parallel to said fixed wall, cam means moving said movable walls, and yielding spring means supporting said cam means, said cam means having an active portion contacting said movable walls and adapted to hold said movable wall in prong-clamping position under the influence of said spring means.
10. In a socket for use with a lamp having a plurality of prongs with shoulders formed thereon the combination of a base, spaced bars mounted on said base, one end of each bar having a stop portion and a notched portion at right angles thereto, a movable member cooperating with each notched portion and forming there-with a socket adapted to receive said lamp prongs with said shoulders contacting said stop portions, a shaft, yielding means supporting said shaft on said base, and rotary cam means mounted on said shaft and cooperating with said movable members to move them into prong-clamping position, said yielding means being moved upon rotation of said cam means to permit the cams to be moved to prong-clamping position and thereafter acting to hold the cams in such position.
11. In a lamp holder, a base, spaced elongated bars pivotally mounted on the base having binding terminals at one end and lamp prongs engaging surfaces at the other end extending transversely of said elongated bars, spring arms secured to the elongated portions of said bars and having portions extending parallel to said transverse end surfaces and forming therewith lamp prong receiving sockets, and manually operated means for moving said spring arms in a direction axially of said bars toward said surfaces for clamping lamp prongs in the sockets.
12. In combination, a base of insulating material having a partition, spaced bars pivotally mounted on said base on opposite sides of said partition, sockets formed on said bars including yielding strip members affixed to a portion of said bars and cooperating with the ends of said bars to receive the prongs of a lamp, and manually operated means for moving said strip members toward the ends of said bars for clamping lamp prongs in the sockets.
13. In a socket for use with a lamp having a plurality of prongs with shoulders formed thereon, the combination of a base, spaced bars pivotally mounted on said base, one end of each bar having a stop portion and a notched portion at right angles thereto, a spring arm secured to each of said bars and having a portion extending in front of the notched portion to form therewith a socket adapted to receive said lamp prongs with said shoulders contacting said stop portions, means engaging said spring arms to flex them into engagement with said lamp prongs to clamp the prongs in said sockets, and manually operable means for operating said first-mentioned means.

FRANK C. DE REAMER. 40
